Patented July 10, 1917.

UNITED STATES PATENT OFFICE.

WILLIAM STRITTMATTER AND HERMAN SCHIMMEL, OF WEEHAWKEN, NEW JERSEY.

LET-OFF MECHANISM.

1,232,623.

Specification of Letters Patent.

Patented July 10, 1917.

Application filed November 10, 1916. Serial No. 130,569.

To all whom it may concern:

Be it known that we, WILLIAM STRITTMATTER and HERMAN SCHIMMEL, citizens of the United States, residing at Weehawken, in the county of Hudson and State of New Jersey, have invented certain new and useful Improvements in Let-Off Mechanisms, of which the following is a specification.

The object of this invention is to provide a simple, compact, and reliable let-off mechanism for looms whereby the warp will be allowed to be delivered only with uniformity and smoothness and entirely without any jerkiness such as characterizes ordinary let-off mechanisms and due principally to the braking means being formed with brake-shoes or brake-straps or otherwise offering extended surfaces and therefore sticking to the warp-beams. According to this invention, the braking means is a warp-controlled lever whose braking surface is preferably convex—therefore offering limited contact—and is disposed relatively between the fulcrum of the lever and the warp-beam, being in the preferred form composed of some such yielding material as rubber or the like.

In the accompanying drawing,

Figure 1 is a side elevation of the let-off mechanism;

Fig. 2 a side elevation, on a larger scale, of the adjoining portions of the brake-lever and warp-beam, the latter appearing partly in section; and,

Fig. 3 is a sectional view on line 3—3 of Fig. 2.

a is a part of the loom frame, *b* the warp-beam, *c* a bar over which the warp *A* extends on its way from the warp-beam to the take-up mechanism (not shown), *d* the brake-lever and *e* a bracket in which the warp-beam is journaled and the brake-lever fulcrumed in the manner to be explained.

The end of the brake-lever which adjoins the warp beam is convex, as at *f*, and comprises a pad *f'* of rubber or other yielding material which will afford good braking contact with the periphery of the warp-beam, being convex in cross section (Fig. 3) so as to conform more or less to the groove in the periphery of the warp beam. Such pad is not indispensable, though it is preferred. Said end of the lever offers a braking surface which is limited, by being convex, and is further disposed relatively between the fulcrum of the lever and the warp-beam. It will therefore be seen that if the lever is

moved one way (the direction in which the warps tend to pull it) it will ultimately clear the warp-beam; whereas if moved the other way (the direction in which gravity moves it) it will return into position to bind against the warp-beam. In actual use, by properly weighting the lever the action of gravity and the pull of the warp may be made so nicely to substantially balance each other that there is practically a merging of the conditions of grip and release of the brake-lever with respect to the warp-beam, so that the warp responds to the pull of the take-up mechanism wholly without jerkiness in even the slightest degree. The free end of the lever is equipped with a roller *d'* under which the warp passes, and a weight or weights *d''*.

In order that the brake-levers may be adapted to fall back in "letting back" the fulcrum stud *g* of the lever is arranged in a slot *h* in the bracket *e*, said slot extending away from the warp-beam in approximately the same direction that the fulcrum stud *g* is from the axis of the warp-beam, and the end of the lever which adjoins the warp-beam has its convex braking face *f* formed as a parabolic curve whose focus is the fulcrum stud *g*. Thus when the lever falls in letting back its braking end continues to hold the beam against turning, stud *g*, on account of the parabolic curve of face *f*, moving outwardly in slot *h* as the lever descends; for limiting this movement of the lever, the stud *g* is adapted to come against the stop *h'* of the slot, the braking end of the lever still of course continuing to hold the beam securely against turning.

Quite aside from this detail, however, we desire to point out that so far as we are aware it is new in a let-off mechanism to provide a brake-lever which, being pivotally movable back and forth in response to the counteracting influences of gravity and the pull of the warp, is movable in the fulcrum support therefor substantially longitudinally of itself, being normally held against the warp-beam by the force which is the resultant of those influences.

In order that the brake-lever may be moved to a position where it is entirely clear of the warp beam, for instance, so that the beam may be freely rotated or removed from its bearings, we provide the slot *h* with a downwardly inclined extension *j* whose lower end *k* affords a stop for the

stud *g*, so that the lever may be shifted in the guideway thus formed to its end *k* and hang pendent therefrom.

Having thus fully described our invention, what we claim as new and desire to secure by Letters Patent is:—

1. In combination, a supporting means, a warp-beam journaled therein, and a warp-actuated brake-lever fulcrumed in said supporting means and having means to be engaged by the unwound portion of the warp extending from the beam and also having a convex braking face at the warp-beam side of its fulcrum.
- 15 2. In combination, a supporting means, a warp-beam journaled therein, and a warp-actuated brake-lever fulcrumed in said supporting means and having means to be engaged by the unwound portion of the warp extending from the beam and also having a 20 yielding convex braking face at the warp-beam side of its fulcrum.
- 25 3. In combination, a supporting means, a warp-beam journaled therein, and a warp-actuated brake-lever fulcrumed in said supporting means and having means to be engaged by the unwound portion of the warp extending from the beam and also having a convex braking face at the warp-beam side 30 of its fulcrum, said lever being bodily shiftable in approximately the same direction as

its fulcrum is from the axis of the warp beam.

4. In combination, a supporting means, a warp beam journaled therein, and a brake-lever fulcrumed in said supporting means and having a braking face at the warp-beam side of its fulcrum, said supporting means having a fulcrum guideway for the lever extending in a line from the warp-beam.

35 5. In combination, a supporting means, a warp beam journaled therein, and a brake-lever fulcrumed in said supporting means and having a convex braking face at the warp-beam side of its fulcrum, said supporting means having a fulcrum guide-way for the lever extending in a line from the warp-beam and then downwardly.

40 6. In combination, a supporting means, a brake-lever pivotally moved back and forth by the counteracting influences of the warp and the action of gravity thereon, and a warp-beam engaged by the brake-lever, said 45 brake-lever being free to move substantially longitudinally of itself in the supporting means toward and from the warp-beam and being normally held against the warp-beam by gravity and the warp.

50 In testimony whereof we affix our signatures.

WILLIAM STRITTMATTER.
HERMAN SCHIMMEL.
